N. ABRAMSON

SOCKET FLASHER

Filed March 6, 1926

Nathan Abramson INVENTOR
BY *J. Stuart Schay* ATTORNEY

UNITED STATES PATENT OFFICE.

NATHAN ABRAMSON, OF BROOKLYN, NEW YORK.

SOCKET FLASHER.

Application filed March 6, 1926. Serial No. 92,862.

This invention relates to thermostatic switching apparatus, and more particularly has reference to devices adapted for intermittently flashing lamps, or the like, such as electric signs, or advertising devices.

It is usual in such devices to have adjusting means for controlling the length of time of the flash or lighting of lamps.

It is customary to install in the circuit 10 an adjusting screw and this screw is usually within the body of the receptacle. In this system, when a change in adjustment is required, such as lengthening or shortening of the flash, the entire receptacle must be removed and the adjustment made.

An object of this invention is to construct 20 a thermostatic switching apparatus or flasher with an external adjusting means controlling an internal thermostatic element. This feature has two objects in view, the first, that of proximity and ease of adjustment and the other, of hiding the thermostatic parts from tampering and protecting same from weather conditions.

25 A further object of this invention is, to provide a socket flasher that can be regulated while the current is on.

A further object of this invention is to 30 provide a socket flasher unaffected either by vibration or external temperatures.

The invention will be more fully understood in connection with the description of the accompanying drawing wherein—

The figure is a view of my improved socket flasher.

I shall show and describe my invention as 40 used in connection with incandescent electric lamps, but it is obvious that it is equally well adapted for any other use where the periodic opening and closing of an electric circuit is desired. As shown, 1 represents a base of porcelain, vulcanized fiber, or the like, having upright receptacle 2, enclosing a metallic shell 3 for receiving a lamp.

45 Within the hollow portion of the base, I arrange a thermostatic switch 4, supported from the base by means of a screw 5.

The thermostatic element 4 is covered partly with asbestos insulation 6. At the 50 end of the element 4, I insert a silver rivet 7.

At the upper face of the base 1, I arrange a horizontal strip of metal 8 held to the base at 9. This strip is punched and tapped at 10 and 11.

55 In the opening 10 of the strip, I arrange a vertical adjusting screw 12 in close proxim-

ity to the receptacle 2 and held firmly by a nut 13.

The bottom or point of the adjusting screw 12 has a silver point 14 set therein. 60

Through the other opening 11, I arrange a screw and nut to hold a wire 15 to said metallic strip 8.

At another portion of the base 1, I attach 65 to the surface an upturned strip of metal 16 having the upturned portion 17 directly under the lamp (not shown) and the other end tapped and held fast to the base by means of a screw 18. This screw also holds in connection to the strip a wire 19. 70

To the metallic shell 3, I form a connection 20, to the thermostatic element 4 by means of screw 5.

At the screw 5 I also attach a resistance wire 22, touching the bare element 4 and 75 wound around the asbestos 6 and extending to the strip 8 and held fast by the nut 13.

The wires 15 and 19 go to the generator.

In operation when a lamp is inserted in 80 the shell 3 and the current is on, traversing along wire 15, along strip 8, then through resistance wire 22, then connection 20, through shell 3, filament of lamp (not shown) then through strip 17 then back to generator. 85

Owing to the high resistance in the wire 22 the power is all consumed in heating the thermostatic element 4, very little of the power or wattage is left to light the filament. The heating of element 4 causes it to bend 90 upwards and makes contact at 7 and 14. The screw 12 can be turned and the distance between 7 and 14 can be varied thus adjusting the time element of the flasher.

When contact between 7 and 14 is made, 95 the resistance wire is shunted and the current flows through the element 4 and directly through the lamp.

The resistance wire will now cool and the thermostatic element will contract and break 100 the connection at 7 and 14 and the previous operation repeated.

A particular feature of this device, is that the adjusting screw 12 is on the open face and adjacent to the receptacle 2 and when 105 adjustment as to the rate of flashing is desired, such adjustment may be made without removing of socket and without inclining of screw driver or other operating implement.

110 The invention is capable of various modifications and changes, without departing

from its scope, and may be combined with various forms of translating devices to obtain a periodic, automatic operation.

Having thus described my invention, I declare that what I claim as new and desire to secure by Letters Patent, is:—

1. In a device of the class described, a receptacle for housing a translating device, a hollow base for housing a thermostatic switch, said switch being perpendicular to the axis of said receptacle, an adjusting means on the outside of the base and adjacent to the receptacle and parallel thereto.
2. In a device of the class described, a receptacle for housing a translating device, a hollow base for housing a thermostatic switch, an adjusting means on the outside of the base and adjacent to said receptacle, said adjusting means also serving as a terminal for the current flowing around the thermostatic switch.

Signed at New York, in the county of New York and State of New York, this 3 day of March, A. D. 1926.

NATHAN ABRAMSON.
